Primary Examiner — Darcey E Gottschalk*Assistant Examiner* — Vanessa Michelle Pursley(74) *Attorney, Agent, or Firm* — Flynn Thiel, P.C.(57) **CLAIM**

The ornamental design for a dispenser packaging, as shown and described.

DESCRIPTION

FIG. 1 is a perspective view of a dispenser packaging showing my new design in a closed configuration;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a perspective view of the dispenser packaging showing my new design in an open configuration;

FIG. 9 is a front view thereof;

FIG. 10 is a right side view thereof;

FIG. 11 is a rear view thereof;

FIG. 12 is a left side view thereof;

FIG. 13 is a top view thereof; and,

FIG. 14 is a bottom view thereof.
